Primary Examiner — Lauren D McVey*(74) Attorney, Agent, or Firm* — Mersenne Law(57) **CLAIM**

The ornamental design for a nasal dilator with relief cuts, as shown and described.

DESCRIPTION

FIG. 1 is a top plan view of a first embodiment of a nasal dilator with relief cuts showing my new design in the unflexed state;

FIG. 2 is a three-quarter perspective view thereof;

FIG. 3 is a top plan view showing my new design in the slightly flexed state;

FIG. 4 is a right side perspective view shown in an in-use state;

FIG. 5 is a top plan view of a second embodiment of a nasal dilator with relief cuts showing my new design in the unflexed state;

FIG. 6 is a three-quarter perspective view thereof;

FIG. 7 is a top plan view showing my new design in the slightly flexed state; and,

FIG. 8 is a right side perspective view shown in an in-use state.

The broken line showing of human facial features is directed to environment and is for illustrative purposes only; the broken lines form no part of the claimed design.
